ELECTRIC DISCHARGE LAMP

Chester H. Braselton, New York, N. Y., assignor
to National Television Corporation, Wilming-
ton, Del., a corporation of Delaware

Application August 9, 1932, Serial No. 628,040

4 Claims. (Cl. 176—122)

This invention relates to electric lamps in which a discharge is caused to be formed in a gaseous medium between two electrodes.

One of the objects of the invention is to provide a discharge lamp in which the electrodes have a maximum active surface per unit of size.

Another object of the invention is to provide a discharge lamp in which the electrodes are maintained relatively cold.

10 Another object of the invention is to provide a discharge lamp in which localization of discharge on the electrodes is prevented.

Still another object of the invention is to provide a discharge lamp in which a high degree 15 of ionization is maintained in the gas.

Another object is to provide a long life discharge lamp.

Other objects of the invention and objects relating to the construction and assembly of the 20 various parts will be apparent as the description of the invention proceeds.

Several embodiments of the invention have been illustrated in the accompanying drawing in which:

25 Fig. 1 is a perspective view partly in section of one form of my improved lamp;

Fig. 2 is a sectional elevational view of a modified form of lamp;

Fig. 3 is a sectional elevational view of still 30 another modification of the invention; and

Figs. 4, 5, 6, and 7 are perspective views of still other forms of electrodes.

Referring now more specifically to the drawing, the construction shown in Fig. 1 which may 35 be the preferred form of the invention, comprises an envelope 10 formed of glass, quartz, or other suitable transparent material, similar in shape to an ordinary electric light bulb and provided at its lower end with an inturned press 11 which

40 is fused to the wall of the envelope. In order to fulfill the objects of the invention, I desire to provide the electrodes with as large amount of active surface as possible, and I have found that this is accomplished very readily by making them

45 out of a fine wire mesh, for instance, one having about 60 wires to the inch each way, the wires being about .007 of an inch in diameter. The material of the electrodes may be any metal

50 which can be easily freed from occluded gases and which is a good conductor of electricity. Such material may be molybdenum, iron, nickel, Monel metal, tantalum, tungsten, and many other metals including even copper. It may be desirable, how-

55 ever, to use a metal having a low contact poten-

tial for the particular gas with which it is to be used.

In this form of the invention I use two electrodes 12 and 13 formed of sheets of wire mesh which are bent in the form of a semi-cylinder. 5 The electrode 13 is bent around a slightly smaller radius than the electrode 12 so that the edges 14 thereof may fit just inside of the edges 15 of the electrode 12 but without coming in contact therewith. The electrode 12 may be reinforced by a 10 semi-circular wire 16 at the top thereof which may be welded to the wire mesh and a second semi-circular wire 17 at the lower edge which may also be welded to the electrode. A support rod 18 may be sealed in the press 11 and may be 15 welded to both the wires 16 and 17 to rigidly support the electrode in position. In like manner the electrode 13 may have a semi-circular wire 19 welded to the inner surface of the upper edge while a wire 20 also bent in the form of a semi-circle may be welded to the inner surface of the lower edge. A support rod 21 also sealed in the press 11 may be welded to the wire mesh at the top and bottom edges to rigidly support the electrode in spaced relation to the electrode 12. Lead-in wires 22 and 23 may be connected respectively to the support rods 18 and 21 for connecting the lamp in a circuit.

With the electrodes mounted in position and the envelope fused to the press as indicated in Fig. 1, the bulb may be connected to an exhaust pump and the temperature of the glass and electrodes raised by placing an oven over the lamp to thoroughly exhaust the envelope and remove all occluded gases from the electrodes. After the 30 gases are removed from the elements and envelope, an ionizable gas may be admitted to the envelope. For this gas I prefer to use one or more of the monatomic gases such as neon, argon, helium, krypton, and xenon, while if desired, certain metal vapors may be added to increase the conductivity or produce color effects. Thus the 35 vapors of mercury, rubidium, caesium, sodium, and others may be added as desired.

Where intensity of illumination is not necessary as for an exit light or night light, the bulb 40 may be filled with neon gas which, as is well known, produces a reddish discharge when a current is passed through it.

The large surface provided by each wire mesh 45 electrode, which exceeds the surface of a solid electrode of the same dimensions, greatly increases the conductivity between the gas and the electrode and permits the electrode to cool readily, as the gas may circulate through it, thus 50

eliminating danger of the formation of overheated spots which might cause localized discharge and possible arcing between the electrodes.

In a lamp of this nature it appears to be desirable to provide the cathode with a greater surface than the anode, but where the lamp is adapted to be used with alternating current, one electrode acts as a cathode during one cycle of the current while the other one acts as a cathode for the other cycle. It is therefore desirable as shown in Fig. 1 to have both electrodes with an equally large surface. However, where the lamp is intended to be used with direct current, it may be desirable to provide the anode with a smaller surface and the construction of Fig. 2 may be used. In this figure the envelope 24 may be provided with a press 25 similar to the envelope and press already described, while the cathode 26 may take the part of a hollow cylinder of wire mesh which may be welded or otherwise supported upon two support rods 27 and 28, one of which, 28, may have a lead-in wire 29 connected to it. Both of the support rods 27 and 28 are sealed in the press 25. The anode 30 may comprise a single rod which may be sealed in the center of the press 25 and may extend upwardly through the center of the cylinder 26 terminating about even with the upper edge thereof. The rod 30 may have a lead-in wire 31 connected to it. In such construction it will be evident that the negative side of the circuit should be connected to the lead-in wire 29 while the positive side should be connected to the lead-in wire 31.

Another embodiment of the invention is illustrated in Fig. 3 where the electrode 32 comprises a hollow cylinder of wire mesh similar to the electrode 26 described above and supported upon support rods 33 which are sealed in a press 34 fused to the envelope 35. The other electrode 40 may also comprise a cylinder 36 of smaller diameter and mounted concentrically of the cylinder 32 upon a support rod 37 which also is sealed in the press 34. Lead-in wires 38 and 39 may be connected respectively to one of the support rods 33 and the support rod 37 to make the necessary connection to the lamp. While the surface of the inner electrode 36 is not as great as that of the outer electrode due to its smaller diameter, it nevertheless is very much larger than the single rod 30 of Fig. 2, and the lamp may be found to give good service on alternating current although direct current may give better results.

In Fig. 4 another form of the invention is illustrated wherein the electrodes 40 and 41 are formed of flat squares of wire mesh. A U-shaped rod 42 may be welded to the electrode 40 to reinforce the two side edges and the bottom thereof in a manner clearly indicated, while a second U-shape rod 43 may be welded in a similar manner to the electrode 41 to reinforce its side and bottom edges. A pair of support rods 44 and 45 may be sealed in the press 46 and welded respectively to the rods 42 and 43, holding the rods and the electrodes in spaced relation to each other as clearly indicated. With this construction the spacing between the electrodes is uniform and the potential drop through the gas between any two opposite points will be the same.

The above modifications of the invention have all been described and illustrated as having wire-mesh electrodes because of their maximum surface and minimum mass, as well as their adaptability for ready cooling, but other means of increasing the surface of the electrode may be

resorted to. In Fig. 5, for instance, a pair of electrodes 47 and 48 have been shown mounted on support rods 49 and 50 respectively, these rods being sealed in a press 51. The electrodes 47 and 48 are formed of metal plates 52 which are perforated with a large number of holes 53 which should have a diameter less than twice the thickness of the plates in order to increase the surface thereof. In Fig. 6 a single electrode 54 is shown mounted upon a support rod 55, and this electrode consists of a plate 56 the surface of which is etched so as to make it irregular and thus increase the surface.

Fig. 7 shows a still further modification of the invention in which the single electrode 57, shown supported upon a support rod 58, is corrugated, crinkled, or otherwise deformed to crowd a large surface of the plate into a small area. Other means for increasing the surface of the electrode may be used such as by making them of standard metal or by wrapping wire around a solid electrode, but none of these appear to give as good results as the wire mesh which reduces the mass to a minimum and increases the surface to a maximum.

It will be seen from the above that I have provided a discharge lamp in which the electrodes may be maintained relatively cool thus preventing arcing or localized discharge and in which the contact resistance between the metal of the electrode and the gas is reduced to a minimum due to the extremely large surface employed.

Many modifications of the invention may be resorted to without departing from the spirit thereof, and I do not, therefore, wish to limit the invention to what has been shown and described except as such limitations occur in the appended claims.

What I desire to claim is:

1. An electric lamp comprising an envelope, a gas within said envelope, a pair of semi-cylindrical electrodes spaced apart within said envelope and having concave sides opposed to each other, one of said electrodes being formed with a smaller radius than the other and having its side edges positioned within the side edges of the other electrode.

2. An electric lamp comprising an envelope, a gas within said envelope, a pair of wire mesh electrodes mounted within said envelope in spaced apart relation, said electrodes being semi-cylindrical in form with one slightly smaller than the other in diameter, and said electrodes being positioned with their concave faces opposed to each other and with the smaller electrode slightly within the larger one.

3. An electric discharge lamp comprising an envelope, an ionizable gas within said envelope, and a pair of spaced apart semi-cylindrical electrodes within said envelope, said electrodes being positioned to form a hollow body having adjacent side edges, the radius of one electrode being less than that of the other, there being only two electrodes within the envelope.

4. An electric lamp comprising an envelope, an ionizable gas within said envelope, a pair of wire mesh electrodes mounted within said envelope in spaced apart relation, said electrodes being curved on an axis substantially parallel to the axis of the lamp and the radius of curvature of one of said electrodes being less than that of the other.

CHESTER H. BRASELTON.
